PUTTY REMOVING TOOL

Loy E. Hiskey, Sterling, Colo., assignor to The Sterling
Mfg. Co., Sterling, Colo.

Application July 29, 1955, Serial No. 37,223

Term of patent 14 years

(Cl. D93—4)

Fig. 1 is a top plan view of a putty removing tool showing my new design;

Fig. 2 is a side view thereof;

Fig. 3 is a bottom view thereof; and

Fig. 4 is an end view thereof.

I claim:

The ornamental design for a putty removing tool, as shown.
